M. FELLOWS

PNEUMATIC AND CUSHION HEAD

Filed Nov. 22, 1921

Inventor:
Mel Fellows
Mason, Finnerick & Lawrence
Attn: [unclear]

UNITED STATES PATENT OFFICE.

MEL FELLOWS, OF CHICAGO, ILLINOIS.

PNEUMATIC AND CUSHION HEAD.

Application filed November 22, 1921. Serial No. 517,088.

To all whom it may concern:

Be it known that I, MEL FELLOWS, a citizen of the United States, residing at Chicago, in the county of Cook and State of Illinois, have invented certain new and useful Improvements in Pneumatic and Cushion Heads; and do hereby declare the following to be a full, clear, and exact description of the invention, such as will enable others skilled in the art to which it appertains to make and use the same.

My present invention relates to carriers used in pneumatic tube systems and has particularly to do with the heads of such carriers.

Primarily it is my object to provide a carrier head admitting of the employment of resilient material having greater lasting qualities than felt now almost universally used and providing for ready replacement of the packing material with new material.

Additionally, it is an object of my invention to provide means for spreading circumferentially the worn packing material of the carrier head in order that the periphery thereof, when reduced by wear, may be enlarged to fit snugly in the tube.

It is a further object of the invention to provide a carrier head which may be inexpensively manufactured but render long service and one which may replace the conventional carrier head without alteration of the carrier or the requirement of special skill or operation for attachment.

It is a still further object of my invention to produce a carrier head which may be secured directly to the carrier, and, also, one in which interchangeability of parts may be successfully practiced.

These and such other objects as may hereinafter appear are obtained by the novel construction, combination and arrangement of the several parts of my device. Reference will now be had to the accompanying drawing forming a part of this specification and in which

Figure 1 is a fragmentary view of a conventional carrier, my carrier head, and a portion of a pneumatic tube;

Figure 2 is a vertical section of one form of my carrier head;

Figure 3 is a similar view of a second

form of my invention illustrating its spreading effect; and

Figure 4 is a similar view of another embodiment of the invention.

Like reference characters are used to designate like parts in the several views in the drawing and in the description which follows.

Referring first to Figure 1, the ordinal 1 designates the end of a pneumatic tube into which the carrier 2 provided with my carrier head 3 is adapted to be inserted.

From Figure 2, it will be seen that the carrier head 3 comprises an outer and an inner compressor or clamp member 4 and 5, both secured upon the carrier 2 by a centrally disposed bolt 6 inserted through an aperture in the end wall 2^a of carrier 2 and secured against displacement by a washer and a nut 7 threaded on said bolt 6 and in engagement with the interior surface of said end wall.

Each clamp or compressor member 4 and 5 is circular in configuration with a thickened central portion, the internal surfaces of said members adjacent their circumferences being arcuately recessed to provide a concave ring seat for a tube engaging member 8, of suitable material and preferably of hollow construction as shown. Intermediate the clamp or compressor members 4 and 5 are a number of separable washers 9.

Instead of the clamping member 5 being a separable part of the carrier, it may constitute the head thereof as indicated by 5^a in Fig. 3. In Fig. 4 both clamping members 4^b and 5^b are provided with similar sockets for the bolt head, both members being interchangeable.

The head of the bolt is preferably counter sunk into an external clamping or compressor member although this construction is optional. As shown in Fig. 4, the outside faces of the clamping members may be flat instead of sloping as shown in Figs. 2 and 3.

The ring member 8 may be of any suitable material as of rubber, either hollow or solid.

When made, it is of such diameter that the clamp members 4 and 5 need not compress upon it to secure a snug fit in tube 1. As it wears down from frictional contact with the walls of tube 1, nut 7 may be re-

5 moved, one of washers 9 taken out and the head reassembled. Compression of the member 8 by clamp members 4 and 5 produce an increased circumference of the former. The removal of spacers 9 may be continued until all are removed after which the ring 8 may be discarded when it is so worn that it admits passage of air around it. Figure 3 shows the compressor members abutting one 10 another.

15 It is apparent that a construction such as I have described provides a flexible carrier head readily adapting itself to the curves, bends and irregularities of the interior surface of tube 1, and one which will keep such interior surface clean and highly polished. No lint or frayed material will be deposited in the tube 1 to retard or stop carriers 2 or to necessitate cleansing the tubes with special 20 carriers as is now required.

25 It is manifest that all possible embodiments of my invention are not herein disclosed and all of its uses are not detailed, therefore, it is not my intention to be limited to the embodiments herein illustrated and described but to include all modifications alterations and changes coming within the scope of the claims hereto appended.

30 In this connection it is proper to add that while I have illustrated an arcuate seat in clamp members 4 and 5 for member 8, a straight or inclined interior surface for said clamp members providing, in cross section,

a rectangular or V-shaped seat for said member 8, may be substituted for the configuration first referred to. 35

What I claim is new and desire to procure by Letters Patent of the United States, is—

1. In a pneumatic tube system, a carrier having circular members and detachable 40 spacing members therebetween, and an elastic washer between said members.

2. A carrier head for use upon carriers in pneumatic tubes, comprising clamp members, detachable spacers between said members, and a tube engaging member surrounding said spacers. 45

3. A carrier head for a carrier in a pneumatic tube comprising a ring member for engaging the inner surface of said tube, 50 compressor members disposed at opposite side of said ring member, a multiplicity of spacers intermediate said compressor members, and a bolt passing through the latter and said spacers, the removal of the spacers 55 one by one admitting of external expansion of the ring member to compensate for circumferential wear.

4. The combination in a carrier tube, of a pair of discs each cut away on adjacent faces 60 to define between them an annular, peripheral groove, a plurality of spacers between said discs and a compressible ring seated in said groove. 65

In testimony whereof I affix my signature.
MEL FELLOWS.
